(57) **CLAIM**

The ornamental design for a supply valve assembly for a hydrant, as shown and described.

DESCRIPTION

FIG. 1 shows a first perspective view of a supply valve assembly for a hydrant.

FIG. 2 shows a second perspective view of the supply valve assembly for a hydrant of FIG. 1; and,

FIG. 3 shows a top view of the supply valve assembly for a hydrant of FIG. 1.

The broken lines in FIGS. 1-3 illustrate the environment of the supply valve assembly for a hydrant and form no part of the claimed invention.
